United States Patent Office

Des. 202,558
Patented Oct. 19, 1965

202,558

COMBINED DOCUMENT READER AND PROCESSOR OR SIMILAR ARTICLE

William Plumb Barbour, Fairfax County, Va., assignor
to Farrington Electronics, Incorporated, Springfield,
Va., a corporation of Massachusetts

Filed Jan. 6, 1965, Ser. No. 83,293

Term of patent 14 years

(Cl. D26—5)

Fig. 1

Fig 2

FIGURE 1 is a front perspective view of a combined document reader and processor or similar article showing my new design.

FIGURE 2 is a back perspective view thereof.

The essential features of my design are shown in full lines.

I claim:

The ornamental design for a combined document reader and processor or similar article, as shown and described.
